[57] CLAIM

The ornamental design for a combined bottle and stopper, as shown and described.

DESCRIPTION

FIG. 1 is a front, elevational view of a combined bottle and stopper showing my new design;

FIG. 2 is a right elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a top, left side perspective view thereof; and,

FIG. 8 is a bottom, left side perspective view thereof.

The design of the combined bottle and stopper is characterized by the combination of glass and metal features thereof on the various surfaces of different shape.
